UNITED STATES PATENT OFFICE.

MAX SCHEUER, OF NEW YORK, N. Y.

DESIGN FOR AN APPAREL-BELT.

SPECIFICATION forming part of Design No. 33,489, dated October 30, 1900.

Application filed October 3, 1900. Serial No. 31,927. Term of patent 7 years.

To all whom it may concern:

Be it known that I, MAX SCHEUER, a citizen of the United States, and a resident of New York city, county and State of New York, have invented and produced a new and original Design for an Apparel-Belt, of which the following is a specification, reference being had to the accompanying drawings, forming part thereof.

Figure 1 is a perspective view of an apparel-belt, showing my new design; and Fig. 2 is a sectional view taken on the line 2-2, Fig. 1.

As shown in the drawings, the leading feature of my design consists of a belt *a*, provided at its front with a narrow strap *b*, which terminates in a concave end piece *c*. This end piece has a rounded head and a con-

tracted neck, which is narrower than the width of strap *b*. Crease-lines *c'* are formed across the end piece and also parallel to its edge. The strap *d*, which carries the buckle *e*, has a similarly-shaped end piece *f*, creased at *f'*.

What I claim is—

The design for an apparel-belt, substantially as herein shown and described.

Signed by me at New York city, county and State of New York, this 2d day of October, 1900.

MAX SCHEUER.
